The ornamental design for a sighting device, as shown.

DESCRIPTION

FIG. 1 is a front, top and right side perspective view of a sighting device showing my new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a right side elevational view thereof;
FIG. 7 is a left side elevational view thereof;
FIG. 8 is a front, top and right side perspective view thereof, showing the sighting device in an open position;
FIG. 9 is a front elevational view of FIG. 8;
FIG. 10 is a rear elevational view of FIG. 8;
FIG. 11 is a top plan view of FIG. 8;
FIG. 12 is a bottom plan view of FIG. 8;
FIG. 13 is a right side elevational view of FIG. 8; and,
FIG. 14 is a left side elevational view of FIG. 8.
